JUSTIN O. SCHWARZ, OF NEW YORK, N. Y., AND GUSTAV BJORKLUND, OF WEST NEW YORK, NEW JERSEY.

ROLL-BOX AND PEDAL MECHANISM.

1,369,554.

Specification of Letters Patent. Patented Feb. 22, 1921.

Application filed October 6, 1917. Serial No. 195,192.

To all whom it may concern:

Be it known that we, JUSTIN O. SCHWARZ, a citizen of the United States, and GUSTAV BJORKLUND, a subject of the King of Sweden, residing at New York city and West New York, New Jersey, respectively, have invented certain new and useful Improvements in Roll-Box and Pedal Mechanism, of which the following is a specification, reference being had therein to the accompanying drawing.

Our invention relates to improvements in the roll box and pedal mechanism of musical instruments, such as player pianos and is illustrated in the accompanying drawings in its application to a player-piano and baby grand of the type.

Referring to said drawings, Figure 1 illustrates in side elevation partly in cross section, the coöperative arrangement of the pedal and roll box mechanism, Fig. 2 is an enlarged detail in perspective with parts broken away, illustrating part of the pedal folding mechanism. Fig. 3 is a view in perspective partly broken away illustrating the position of the roll box beneath the keyboard. Fig. 4 is a perspective view partly broken away showing the position of the roll box beneath the keyboard with the keyboard omitted. Fig. 5 is a perspective view with parts broken away illustrating the roll box in upright position in front of the keyboard. Fig. 6 is an enlarged cross sectional view of part of the roll box showing certain buttons for controlling the pneumatic playing of the instrument and Fig. 7 is an enlarged detail partly broken away illustrating part of the locking mechanism for the roll box.

Referring now more particularly to Figs. 1—2, 8 indicates the pedal cabinet beneath the piano, and 9 a slideway bearing for establishing coöperative connection between the roll box and pedal mechanism. 10 indicates the roll box after it has been drawn out from beneath the front of the piano keyboard in which position it may be turned upwardly as shown in Fig. 5, and 10' indicates the same pushed in beneath the keyboard of the piano in the position shown in Fig. 3.

The roll box, it will be observed is connected by a rod 11 to the slide members 12—13 guided upon the bar 9. The slide member 12 is free to slide upon the bar 11,

it is also free to slide upon the slide bearing 9, but is shifted by the stops 14—15. The slide member 13 is provided with a suitable binding screw 16, which secures it to the bar 11 so that when the roll box 10 is out in the position shown in full outline, the pedal mechanism below is in the position shown in full outline, and when the box 10 is pushed in beneath the keyboard as shown in dotted outline, the pedals are folded up within the cabinet 8 as shown in dotted outline, the pedal mechanism being as follows:

17 indicates a suitable base support or bracket preferably cast from metal and provided with overhanging inside flanges 18—18' upon which are secured at each side substantial L-shaped connecting bars such as 19 preferably pivoted at the base of the over-hanging flanges as indicated at 20 and 21 at the other end secured to the toe-plate 21 provided with toes such as 22, said toe-plate being pivotally secured to the foot-board 23 at 24 as shown. At the upper part of the foot-board is also pivotally secured a connecting rod 25 which at its lower extremity is secured to the stem 26 of the Y-shaped bracket pivoted at 29. The toe-plate 21 is also pivotally connected by the rod 27 to the rod 28 upon the bar 29 shown to advantage in Fig. 2 and 30—31 are coiled springs upon the bar 29 wound oppositely and connected to the bar 28 and to the base support 17. The other leg 32 of the Y-shaped member is intended to be connected 90 to the bellows.

33 indicates a rod pivotally connected to the rod 28 at the bottom and to the slide member 13 at the top and from all of it it will be seen that as the roll box 10 is pushed inwardly to the position shown in dotted outline at 10' the rod 33 being carried back at the upper part turns upwardly upon the rod 28 thereby rotating the pedal anti-clockwise and at the same time lifting the foot-board 23 until the entire mechanism is folded in the position shown in dotted outline.

The roll box shown to better advantage in Fig. 5 is pivotally mounted at 34 upon the block 35 provided at the top with I-blocks 105 36 which are adapted to slide between the plates 37—38 secured beneath the piano, thus providing for a longitudinal sliding and support for the roll box as a whole.

39 indicates an L-shaped bar provided 110

with springs such as 40 which tend to throw the leg 41 thereof at all times against the roll box so that when the roll box is drawn outwardly and turned upwardly as shown in Fig. 5, the end 41' of said bar engages the ledge 42 of the link 43 which is provided with elongated slot 44 adapted to receive the pin 45 in the side wall 46 of the roll box. This link 43 is also pivotally connected to the link 47 pivoted at 48 to the side of the box as shown and connected by spring 49 tending to keep the button 50 projected outwardly. When it is desired to turn the roll box down and under the keyboard by pressing upon the button 50, the link 43 is turned slightly anti-clockwise upon the pivotal slide bearing 41-45 thereby releasing its engagement with the bearing 41 and allowing the box to be manipulated as desired when the box is again drawn out, the end 41' of the lever 41 falls after the link 43 under influence of the springs 40 until it is again receded, locking the box in upright position as shown.

51 indicates buttons at the top of the roll box projected by springs such as 52 upon the stems 53 which are secured at the lower ends to the blocks 54 which under influence of the springs 52 are normally projected

upwardly against the felt buttons 55 thereby closing the ports 56 in said blocks. The pins 57 serve as guides and the admission of atmospheric air to the tubes 58 is thus manually controlled, said tubes being preferably of rubber for flexibility and connecting the various parts of the stem intended to be controlled by said buttons.

Of course it will be understood that various modifications may be made in the construction and arrangement of the parts without departing from the spirit of invention as claimed.

We claim:

In combination with a musical instrument, a folding pedal mechanism and a sliding music roll box, said pedal mechanism pivotally connected at three essential points by links, and a link pivotally connecting one of said links with the sliding mechanism of said roll box.

In testimony whereof we hereunto affix our signatures in the presence of two witnesses.

JUSTIN O. SCHWARZ.
GUSTAV BJORKLUND.
